Primary Examiner — Michael A Pratt(57) **CLAIM**

The ornamental design for an archery bow rotatable member, as shown and described.

DESCRIPTION

FIG. 1 is an angled isometric view of the archery bow rotatable member.

FIG. 2 is a front view of the archery bow rotatable member.

FIG. 3 is a back view of the archery bow rotatable member.

FIG. 4 is a left side view of the archery bow rotatable member.

FIG. 5 is a right side view of the archery bow rotatable member.

FIG. 6 is a top view of the archery bow rotatable member; and,

FIG. 7 is a bottom view of the archery bow rotatable member.

The broken lines in the Figures are for illustrative purposes only. The broken lines form no portion of the claimed design.

1 Claim, 5 Drawing Sheets(56)
